Primary Examiner — Marissa J Cash*Assistant Examiner* — Altaira J Swangin(74) *Attorney, Agent, or Firm* — Cantor Colburn LLP(57) **CLAIM**

The ornamental design for a digital board, as shown and described.

DESCRIPTION

FIG. 1 is a front perspective view of a digital board showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is another rear perspective view thereof; and,

FIG. 10 is another front view thereof.

The evenly dashed broken lines illustrating portions of the digital board form no part of the claimed design.
